UNITED STATES PATENT OFFICE.

LESLIE L. TIRRELL, OF NEW TROY, MICHIGAN.

SPRAY GUN.

Application filed April 13, 1922. Serial No. 552,292.

To all whom it may concern:

Be it known that I, LESLIE L. TIRRELL, a citizen of the United States, and a resident of New Troy, in the county of Berrien and State of Michigan, have invented a new and useful Improvement in Spray Guns, of which the following is a full, clear, and exact description.

My invention relates to improvements in spray guns, and it consists in the combinations, constructions, and arrangements herein described and claimed.

An object of my invention is to provide a device of the character described in which a liquid is thoroughly atomized and subsequently projected through a suitable nozzle.

A further object of my invention is to provide a device of the character described in which the atomized liquid may be projected at will through one or two nozzles by merely turning the central liquid feed tube.

A further object of my invention is to provide a device of the character described in which the liquid may be thoroughly atomized and projected through a relatively long tube attached to the nozzle, as in spraying ceilings or the like.

A further object of my invention is to provide a device of the character described which is simple in construction, easy to operate, and which is thoroughly practical commercially.

Other objects and advantages will appear in the following specification, and the novel features of the invention will be particularly pointed out in the appended claims.

My invention is illustrated in the accompanying drawings, forming part of this application, in which

Figure 1 is a partial sectional view of an embodiment of my invention, the forward portion thereof being turned 90° on its axis for the purpose of illustration,

Figure 2 is a sectional view along the line 2—2 of Figure 1,

Figure 3 is a sectional view along the line 3—3 of Figure 1,

Figure 4 is a sectional view along the line 4—4 of Figure 1, and

Figure 5 is a sectional view of a modified form of the nozzle.

In carrying out my invention, I provide a cylindrical barrel 1 having secured thereto at its rearmost end a metal fitting 2 having an integral inlet portion 3 threaded at its

outermost end for engagement with an air hose 4 or the like. A bore 5 is centrally disposed through the rear end of the fitting 2, and a packing ring 6 is provided and arranged to engage threads 7 on the outer surface of the fitting adjacent the mouth of the bore 5. A relatively slender tube 8 is rotatably disposed within the barrel 1, the bore 5 providing bearing at one end thereof. A valve 9 is connected to the outermost end 65 of the tube 8 and serves as a means for controlling the flow of paint or other solution into the tube 8.

The forward end of the barrel 1 is provided with a nozzle 10, shaped in the form of a cap, and having threads 11 on the inside walls thereof. The threads 11 are arranged to engage threads upon the outer surface of the barrel 1 adjacent the outer end of the barrel, as shown in Figure 1. For the purpose of illustration, the nozzle 10 has been turned 90° as it is viewed in Figure 1. This is to show the fan-like arrangement of the apertures 12 and 13 extending through the front wall of the nozzle, one on each side 75 of its central point. A short metal tube 14 is axially disposed through the front wall of the cap 10, and is arranged to extend within the barrel 1 and a short distance in front of the cap 10.

The forward portion of the tube 8 has connected thereto a spool-shaped member 15 having a centrally located bore 16. An integral partition 17 is disposed in the bore 16 intermediate its length. The rearmost edge 90 of the member 15 is provided with an outwardly extending flange 18, which flange is adapted to closely engage the inner walls of the barrel 1, and rotatably bear thereagainst. The tube 8 is fixedly connected to the member 15 and is provided with four radially extending equally spaced apart openings 19. These openings 19 are placed into registration with openings 20 through the sleeve-like portion 21 of the member 15. Four 100 transverse openings 22 are provided in the flange 18, and are in registration with the axes of the openings 19 and 20.

A second outwardly extending flange 23 is provided intermediate the length of the 105 member 15. The flange 23 is arranged so that it does not contact the inner walls of the barrel 1, but provides an annular space therebetween. The flange 23 is also provided with transverse openings 24, which 110

openings are in exact registration with the openings 22 in the flange 18. The bore 16 on the outer side of the partition 17 is adapted to receive the inwardly extending portion of the tube 14, and thus provides a suitable bearing for the member 15 and the outer end of the tube 8. A spiral compression spring 25 is disposed intermediate the inner end wall 26 of the fitting tube, and a washer 27 carried by the tube 8. Thus, the tube 8 is constantly pressed toward the nozzle 10 and the member 15 is in close contact with the inner surface of the nozzle cap 10.

The inwardly extending portion of the tube 14 is provided with two diametrically opposed elongated openings 28. The member 15 is also provided with two elongated openings 29, which openings are adapted to be moved into registration with the openings 28 when the tube 8, carrying the member 15, is rotated.

The outer end of the member 15 is provided with a pair of diametrically opposed outwardly extending shutters 30 integral therewith. These shutters are more clearly shown in Figure 4, and are so disposed relative to the member 15 that they are arranged to be moved into registration with the openings 12 and 13 in the nozzle 10 when the elongated openings 29 in the member 15 are in registration with the openings 28 in the tube 14. This is more clearly shown in Figure 4. In Figure 1 the annular portion concentric with the member 15 between the shutters is indicated at 30^a.

From the foregoing description of the various parts of the device, the operation thereof may be readily understood. In using my spray gun, I connect the inlet 3 to an air compressor, or some similar device. I connect the valve 9, by means of a suitable hose connection, to a reservoir of paint. If it is desired to spray an object that is out of the ordinary reach of the user, I use what I choose to term the "long distance" nozzle, i. e., the short tubular member 14 having a single outlet. This outlet, formed of the tube 14, may be connected by a suitable tubular connection to convey the atomized liquid for the necessary distance. When the device is so used, I manually turn the tubular member 8 so that the member 15 is rotated to cause the shutters 30 to move into registration with the openings 12 and 13. As this occurs, the elongated openings 29 will be moved into registration with the openings 28. The course of the paint or liquid in the reservoir will be as follows:

The paint or liquid will enter through the tube 8 and be projected into the outer portion of the barrel 1 through the four radially extending openings 20 in the member 15. The jets of paint thus formed will be in exact registration with the openings 22

through the flange 18, and as air is passing through these openings at a relatively high velocity, the paint in the jets from the openings 20 will be atomized. A portion of the finely divided product will pass directly through the openings 24, and a part will pass through the annular space between the flange 23 and the inner wall of the barrel 1. This atomized liquid will then be blown inwardly through the two diametrically opposed openings 28 and 29, and ultimately out of the short tube 14 in the form of a single finely divided blast of atomized liquid or paint.

If it is desired to use the device for spraying at a relatively short distance, then I manually rotate the tube 8 until the member 15 and the nozzle 10 are disposed in the position shown in Figure 1. The atomizing action of the device in the rearmost portion of the member 15 will be precisely as described, but the course of the atomized paint or liquid in leaving the gun, will be directed through the openings 12 and 13. The openings 12 and 13 are arranged in fan-like position so that the spray will be distributed over a larger area than if both of the openings were parallel. At the same time, the opening 29 is out of registration with the opening 28 and the shutters 30 are out of registration with the openings 12 and 13.

In Figure 5, I have shown a modified form of the nozzle 10, in which I have shown in place of the short tube 14, an integral inwardly extending stub shaft 31. The bore 16 is adapted to receive the stub shaft 31 and provides bearing for the member 15. In this form of nozzle, I provide additional openings 32 and 33, thus increasing the distribution of the atomized liquid or paint.

I claim:

1. A spray gun comprising a barrel, a detachable nozzle therefor, said nozzle having discharge openings therethrough, a short tube disposed transversely through the end wall of said nozzle between said discharge openings, means for admitting a paint solution and air under pressure to said barrel, whereby said paint solution may be atomized, and means for selectively discharging the atomized paint solution through said discharge openings and said tube at will.

2. A spray gun comprising a barrel, a detachable nozzle therefor, said nozzle having discharge openings therethrough, a short tube disposed transversely through the end wall of said nozzle between said discharge openings, means for admitting air under pressure to said barrel, a tube for conveying a paint solution into said barrel, means for projecting the air under pressure in jets upon said paint solution as it is delivered from said last named tube, whereby said paint solution may be atomized, and means

for selectively discharging the atomized paint solution through said discharge openings and said first named tube at will.

3. A device of the character described comprising a barrel, a tube disposed in said barrel for conveying a paint solution or the like, said tube being rotatably mounted on said barrel at one end, a nozzle having openings therethrough supported upon the opposite end of said barrel, a spool-shaped

member carried by said tube and having a shutter arranged to be moved into registration with the openings in said nozzle when said tube is rotated, and means carried by said nozzle for rotatably supporting said 15 spool-shaped member, whereby the entire tube is rotatably mounted relative to said barrel.

LESLIE L. TIRRELL.
